UNITED STATES PATENT OFFICE.

JAMES WARES BRYCE, OF BLOOMFIELD, NEW JERSEY, ASSIGNOR TO THE AEOLIAN COMPANY, A CORPORATION OF CONNECTICUT.

EXPRESSION-DEVICE CONTROL.

1,305,191.

Specification of Letters Patent. Patented May 27, 1919.

Application filed December 22, 1916. Serial No. 138,466.

To all whom it may concern:

Be it known that I, JAMES WARES BRYCE, a citizen of the United States of America, and a resident of Bloomfield, county of 5 Essex, and State of New Jersey, have invented certain new and useful Improvements in Expression-Device Controls, of which the following is a specification, reference being had to the accompanying drawing, forming a part thereof.

My invention relates to improvements in remote control for expression devices for musical instruments, and more specifically for means actuated by alternating electric 15 currents for controlling the expression devices for phonographs, such for example, as a valve for varying the volume of sound produced by such an instrument.

Its object is to provide a simple, efficient 20 and sensitive electro-responsive actuating mechanism for expression devices, with a manually operable graduated current control device for alternating currents, by means of which a person at any desired distance from a musical instrument, may control such an expression device at will.

In order that my invention may be thoroughly understood, I will now proceed to describe the same in the following specification, 30 and then point out the novel features thereof in appended claims.

Referring to the drawings:

Figure 1 is a side elevation partly in section, of certain parts of a phonograph or 35 the like, with actuating and control devices embodying my invention applied thereto, the latter being shown diagrammatically.

Fig. 2 is a diagrammatic representation of a modified form of sensitive relay which 40 forms a part of this invention.

Like characters of reference designate corresponding parts in all the figures.

10 designates the tone arm of the instrument to be controlled, and 11 a part of its 45 sound chamber. 12 is the expression device, in this case a valve arranged to be moved by a rod 13 toward or away from its seat to thereby produce more or less restriction to the size of the sound passage and to thereby 50 vary the volume of sound emitted from the instrument.

The electro-responsive motor is designated generally by the reference numeral 20. This motor comprises a pair of similar solenoids 21-22, a common core 23, and a dash-

pot 24 connected with the core. 25 is a bell crank lever pivoted at 26 with one of its arms connected with the core 23 by a link 27 and its other arm connected with the valve rod 13 by means of a rod 28 and another 60 bell crank lever 29.

30 is a rod extending rigidly from the bell crank lever 25 in carrying a weight 31 by means of which the bell crank lever and the different elements which are connected 65 therewith, may be counterbalanced to a desired extent.

32 is another arm rigidly connected with but insulated from the bell crank lever 25. This carries at its outer end an electrical 70 contact 33 which is adapted to slide over and make electrical connection with various points on a rheostat 34 as the positions of the bell crank lever 25 and of the valve 12 are changed.

40 is a manually operable current-varying or control device which comprises a rheostat 41 similar in resistance to the rheostat 34, a movable contact 42 and an actuating 75 thumb or finger piece 43.

A sensitive relay is interposed between this manual control device and the solenoids 21-22. This relay is designated generally by the reference numeral 50 and comprises a pair of vertically disposed solenoids 51-52, 80 for each of which is provided a laminated core 53-54, which cores are suspended by springs 55 and 56. These springs are each provided with adjusting screws 57-58. 85 60-61 are disks connected with the solenoid 90 cores 53 and 54 respectively and immersed in liquid contained in small receptacles 62-63. These parts form damping devices for the solenoids.

64 is an inverted T-shaped lever. To the 90 outer ends of the horizontal arm of this lever the cores 53 and 54 are pivotally connected. Its vertical arm carries a pin 65 which projects into a slot 66 in an arm 67 which is pivoted at 68. When the solenoids 1 51-52 are not energized or when they are energized to exert equal pulls upon their cores, the parts will assume the positions in which they are shown in the drawings, with the slot 66 parallel with the cores 53-54 1 and the springs 55-56. A flexible contact member 69 is connected with but insulated from the arm 67 and extends upwardly therefrom in alignment with the slot 66.

70 designates an alternating current gen- 1

erator. From one of the mains thereof a circuit extends through a resistance 71 and by branches to and through the windings of solenoids 51 and 52. The circuit which passes through solenoid winding 51 continues through a wire 72 to the rheostat 34; thence it continues through contact 33, wires 73 and 74, through the manually operable switch 75 to the other main of the generator 70. The other circuit which passes through solenoid winding 52 continues through a wire 76 to rheostat 41, thence it continues to contact 42 and wires 77 and 74, through switch 75, back to the other main of the generator 70.

As the number of convolutions in the solenoid windings 51 and 52 are equal the currents passing through these two solenoids will be the same when the contacts 33 and 20 42 of the rheostats 34 and 41 are in the positions shown, to exert equal pulls upon their cores 53 and 54 so that they will cause the pin 65 to move downward in the slot 66 without affecting the position of the pivoted arm 67.

If the operator now moves the contact 42 over the rheostat 41, the current in solenoid 52 will be reduced thereby, thus causing the core 54 to be raised by the spring 56 out of solenoid 52 to some extent. This at once causes the pin 65 to push the lower end of the pivoted arm 67 over to the left and the flexible contact arm 69 to the right.

80 is a stationary contact against which 35 this flexible contact arm 69 will then move. 81 is a wire from one of the mains of the generator 70 to the flexible contact arm 69. 86 is a wire from the stationary contact 80 to the winding of the solenoid 21. The other 40 end of this solenoid winding is connected by wires 83 and 84 through switch 75 to the other main of the generator 70. A current passing through the circuit thus pointed out will cause the solenoid 21 to raise the core 45 23 and this movement retarded by the dash pot 24 will, through the mechanical connections hereinbefore described, cause the valve 12 to be raised. It will, at the same time, cause contact 33 to be moved over 50 rheostat 34 until an amount of resistance thereof equal to the amount of the resistance of rheostat 41 which the operator has put in circuit with solenoid 52 when the effect of solenoid 51 upon its core 53, will be reduced to the same amount that the pull of 55 the solenoid 52 upon its core has been reduced. The arm of the T-shaped lever 64 which carries the pin 65 will then resume a vertical position and cause the flexible contact 69 to be moved away from the stationary contact 80, thus opening the circuit through solenoid 21 and stopping further movement of the core 23 and the parts with which it is connected. If the operator now

inserts more of the resistance of rheostat 65 41 in the circuit of the solenoid 52 the circuit through solenoid 21 will again be closed between contacts 69 and 80 and the core 23 will be given a further upward movement.

When the operator moves the contact 42 of the remote control device, back in the opposite direction, he will thereby strengthen the current through solenoid 52 causing it to have a greater pulling effect upon its core 75 54 than has the solenoid 51. In this case the flexible contact 69 will be moved against a stationary contact 85 and a circuit will thereby be closed through wires 81 and 82 to the winding of solenoid 22 from whence the circuit continues through wires 83 and 84 and switch 75 to the other main of generator 70. In this case the solenoid cores 23 will be pulled downward and this will move valve 12 farther away from its seat and will at the same time move contact 33 over rheostat 34 until the part of the resistance thereof in circuit with solenoid 51 balances the amount of resistance of rheostat 41 which is in circuit with solenoid 52. The sensitive relay 50 90 will again come into its balanced position and will cause the flexible contact arm 69 to move away from stationary contact 85, thus breaking the circuit through solenoid 22 and causing the parts which are controlled thereby, to again come to rest.

By this simple means it is possible for an operator at any desired distance from the instrument to cause the valve 12 to be moved in either direction and to be given any desired amount of movement.

There are but two wires between the remote control device 40 and the sensitive relay 50, the latter, together with the valve actuating solenoids 21-22 and their connected parts, may be installed within the sound producing instrument itself so that it is a simple matter to remove the control device 40 to any desired distance from the instrument.

It is my intention to have the wires leading to the manual control device flexible so that the operator will be able to freely move the hand in which it is held.

The arrangement shown in Fig. 2 is a modified form of sensitive relay. This comprises two alternating current solenoids 51^a and 52^a with cores 53^a and 54^a. In this case the solenoids are connected by springs 90 and 91 with the lower end of an arm 92 120 which is pivoted at 93. The upper end of this arm carries a flexible contact 94 which is adapted to be moved against stationary contacts 80 or 85 to thereby close a circuit through either solenoid 21 or solenoid 22. 125 The method of balancing the pull of solenoids 51^a and 52^a upon their respective cores, distributing and restoring this magnetic bal-

ance is similar to that described in connection with Fig. 1, so that a repetition of the description of operation is not necessary.

The invention is shown as applied to a 5 talking machine or phonograph, but I do not intend to limit myself to this specific use.

The sensitive relay 50 is, I believe, novel and useful in conjunction with other devices actuated by alternating currents, and I 10 therefore do not intend to limit myself to the use to which it is shown applied in the drawings. I have illustrated several forms of certain parts of the apparatus to show that I do not limit myself to any specific 15 form or construction and in fact intend no limitations other than those imposed by the appended claims.

What I claim is:

1. An expression device for musical instruments comprising a movable member, an alternating current reversible motor arranged to actuate said member different desired amounts, a reversing switch comprising a pair of actuating alternating current 25 solenoids, circuits therefor and circuit closers for the motor, said reversing switch having a movable contact and stationary contacts, a lost motion connection between said solenoids and the movable contact, a 30 current varying device connected to be actuated by the motor an amount proportional to the movement of said member, said current varying device being in one of the actuating solenoid circuits, and a remote control device comprising a manually adjustable current varying device in the other actuating solenoid circuit.

2. An expression device for musical instruments comprising a movable member, an alternating current reversible motor arranged 40 to actuate said member different desired amounts, a reversing switch comprising a pair of actuating alternating current solenoids, circuits therefor and circuit closers for

the motor, said reversing switch having a 45 pivoted arm, a contact arranged to be moved by said arm and stationary contacts, a lever, solenoid cores connected therewith, resilient means for supporting said lever, and a lost motion connection between said lever and 50 said pivoted arm; a current varying device connected to be actuated by the motor an amount proportional to the movement of said member, said current varying device being in one of the actuating solenoid circuits, 55 and a remote control device comprising a manually adjustable current varying device in the other actuating solenoid circuit.

3. An expression device for musical instruments comprising a movable member, an alternating current reversible motor arranged to actuate said member different desired amounts, a reversing switch comprising a pair of actuating alternating current 60 solenoids, circuits therefor and circuit 65 closers for the motor, said reversing switch having a pivoted arm, a contact arranged to be moved by said arm and stationary contacts, an inverted T-shaped lever, a pin and slot connection between the vertical arm of 70 said lever and the pivoted arm, laminated solenoid cores spaced apart and connected with the horizontal arm of the lever and vertical adjustable springs connected with said horizontal arm of the lever supporting the lever 75 and the solenoid cores; a current varying device connected to be actuated by the motor an amount proportional to the movement of said member, said current varying device being in one of the actuating solenoid 80 circuits, and a remote control device comprising a manually adjustable current varying device in the other actuating solenoid circuit.

In witness whereof, I have hereunto set my hand this 20th day of December, 1916.

JAMES WARES BRYCE.
